[57] **CLAIM**

The ornamental design for a fermentation bung, as shown and described.

DESCRIPTION

FIG. 1 is a top and side perspective view of a fermentation bung showing my new design;

FIG. 2 is a top plan view thereof;

FIG. 3 is a side elevational view thereof, the opposite side being a mirror image thereof;

FIG. 4 is a bottom plan view thereof;

FIG. 5 is a view taken about lines 5—5 of FIG. 3; and,

FIG. 6 is a view taken along lines 6—6 of FIG. 3.
